(57) CLAIM

I claim, the ornamental design for a tripod hunting stand, as shown and described.

DESCRIPTION

FIG. 1 is a side elevational view of a tripod-hunting stand showing our new design;

FIG. 2 is a top plan view thereof; and,

FIG. 3 is an enlarged fragmentary side elevational view of the hinge element.

The broken lines showing a boat seat is for illustrative purposes only and form no part of the claimed design.
